C. R. LAMBERT.
VAPOR BURNER FURNACE.
APPLICATION FILED MAR. 1, 1912.

Patented Apr. 27, 1915.

2 SHEETS—SHEET 2.

UNITED STATES PATENT OFFICE.

CHARLES R. LAMBERT, OF DETROIT, MICHIGAN, ASSIGNOR TO CLAYTON & LAMBERT MANUFACTURING COMPANY, OF DETROIT, MICHIGAN, A CORPORATION OF MICHIGAN.

VAPOR-BURNER FURNACE.

1,136,965.

Specification of Letters Patent. Patented Apr. 27, 1915.

Application filed March 1, 1912. Serial No. 680,993.

To all whom it may concern:

Be it known that I, CHARLES R. LAMBERT, a citizen of the United States of America, residing at Detroit, in the county of Wayne 5 and State of Michigan, have invented certain new and useful Improvements in Vapor-Burner Furnaces, of which the following is a specification, reference being had therein to the accompanying drawings.

10 The invention relates to furnaces more particularly designed for use in heating of soldering irons, the melting of soft metal and other similar uses.

It is the object of the invention to simplify and cheapen the construction and to this end the invention consists in the peculiar construction, arrangement and combination of parts as hereinafter set forth.

In the drawings,—Figure 1 is a side elevation of the furnace; Fig. 2 is a perspective view of the hearth and hood construction; Fig. 3 is a longitudinal section therethrough; and Fig. 4 is a cross section. Fig. 5 is a perspective view of the hearth-plate 25 with its depending flange.

A is a tank for liquid fuel such as gasoline, upon which is mounted on a standard B, a frame C for supporting the burner, hearth-plate and hood. As heretofore constructed it is usual to make the hearth and hood, as well as the burner, of cast metal. In the present construction they are formed from sheet metal stampings which is not only a cheaper construction to manufacture 30

but reduces the weight of the structure which is desirable as the device is usually carried by hand. In detail, D is a pan struck up from sheet metal to form a bottom and integral sides with rounded corners. The front side is cut-away at E for the passage of the valve stem therethrough, while the bottom of the pan beneath the burner valve is depressed at F to form a starting cup. The upper edge of the sides 40

45 G of this pan have the outwardly extending stiffening flange H which also forms a support for the hood section I. The latter is also formed from sheet metal stampings having the horizontal base flange J and a

50 down-turned marginal flange K, the latter embracing the flange H of the pan. Above the flange J is a conical portion L which is circular at its upper end and is attached by riveting or otherwise to a cast metal stiffening ring M having lugs N projecting inward

therefrom to support a pot or ladle. The front of the hood L is cut-away at O for the insertion of soldering irons or other tools to be heated. There is also a hearth plate P formed of sheet metal which is interposed between the flange J of the member I and the pan D. This hearth plate projects outward beyond the hood and at its inner end has a down-turned flange Q which separates the combustion chamber from the portion of the pan in which the valve is located. The burner R is preferably of cast construction, being provided with a central air and vapor mixing tube R' and slotted tubes R² on opposite sides thereof connected to the mixing tube by the end cross tube R³. The vaporizer is formed by a tube S which passes through the hood above the burner but at one side thereof, and then turns downward in front of the flange Q and is 65 connected with the inlet valve T. At its opposite end the tube S passes out from the hood and is connected with a downwardly extending conduit U leading into the tank. 70

The construction described being almost 80 completely made of wrought metal is less liable to be broken than cast construction and is also lighter and stronger. A suitable carrying handle or bail V is provided, this being attached to ears W riveted to the opposite sides of the hood below the ring M and there is also a cover X for closing the opening in the ring M when the pot or ladle 85 is not used.

As the opening a in the tubes R² is located 90 at the sides a deflecting plate Z is provided which as shown has a segmental portion b engaging the tube R' and apertured at c to receive a lug d at the center of the member R'. The segmental portion terminates in 95 outwardly extending flanges e which are positioned below the plane of the opening a. Adjacent their outer edges these flanges are provided with legs f which rest upon the bottom D. Adjacent the middle of the deflecting plate is arranged a dividing partition h. The construction just described forms a very effective means of spreading the flame. 100

What I claim as my invention is:

1. In a furnace, the combination with a tank, a standard rising therefrom, a spider frame supported on said standard, a pan secured to said spider frame, burners and a mixing tube in said pan, and a deflecting 110

plate engaging said tube and having portions projecting into operative relation to the burners for the purpose described.

2. In a furnace, the combination with a tank and a standard mounted thereon, of a sheet metal structure mounted on said standard comprising a pan having a bottom and integral sides flanged at their upper edge, a hearth-plate of sheet metal resting on said flange and having a depending flange extending into the pan, a hood formed of sheet metal having a circular opening at the top thereof and flanged at its lower end to rest upon said pan and to embrace the flanged edge thereof, and a reinforcing ring of cast metal secured to the upper end of said hood.

3. In a furnace, the combination with a tank and a standard rising therefrom, of a sheet metal structure supported on said standard comprising a pan having upwardly extending integral sides flanged at their upper edge, a hearth-plate supported at one end of said pan having a downward extending flange, a hood arranged above said pan and flanged to rest thereon and to engage the flanged edges of the pan, said hood being cut-away over said hearth-plate, a burner arranged within said pan, a vaporizer extending through said hood, and a vapor controlling inlet valve arranged beneath said hearth-plate and connected with said vaporizer.

4. A furnace comprising a tank, a standard rising therefrom, a spider frame supported on said standard, a pan formed of sheet metal secured to said spider frame having integral sides and a flanged upper edge, a burner and mixing tube in said pan, an inlet valve in front of said burner, a hearth-plate formed of sheet metal having a down-turned flange dividing the portion of said pan containing said burner from that containing said inlet valve, a hood formed of sheet metal above said pan and hearth-plate and flanged for engagement therewith, a vaporizing tube passing through said hood above said burner at one side thereof and downward through said hearth-plate to said valve.

5. In a furnace, the combination with a tank, a standard rising therefrom, a spider frame upon said standard, and a sheet metal structure upon said frame comprising a pan having integral upwardly extending sides with a flanged upper edge, a hearth-plate overlying a portion of said pan having a depending flange, and a hood having a hori-

zontal flange resting on said hearth-plate and pan, a down-turned marginal flange, and a tapering upwardly extending body portion, said body portion being cut-away above said hearth-plate, the upper edge of said body being of circular form and a cast metal reinforcing ring secured to the upper edge of said hood and having inwardly extending lugs thereon for supporting the pot or ladle.

6. In a furnace, the combination with a tank, a standard rising therefrom, a spider frame supported on said standard, a pan secured to said spider frame, a mixing tube in said pan, burners arranged upon opposite sides of said mixing tube, and a deflecting plate engaging said tube and having laterally extending portions projecting into operative relation to the burners, for the purpose described.

7. In a furnace, the combination with the tank of a standard rising therefrom, a spider frame supported on said standard, a sheet metal pan with flanged upper edge thereon secured to said spider frame, a hood having a corresponding flange and fitting upon said pan, a vaporizing tube above said pan and within said hood, a mixing tube connected to the vaporizing tube by means of a valve, an end cross tube connecting the vaporizing tube, slotted tubes arranged upon opposite sides of said mixing tube, said slotted tubes being closed at one end and connected to said end cross tube, a deflecting plate having a segmental portion engaging the mixing tube and terminating in outwardly-extending flanges positioned below the plane of the openings in the slotted tubes, a dividing partition arranged adjacent the middle of the deflecting plate, and a hearth plate with a downward projecting flange overlying a portion of said pan.

8. In a furnace, the combination with a hood and pan forming a combustion chamber, of a valve positioned therein, a hearth plate positioned in the plane of the meeting edges of said hood and pan, said hearth plate projecting outward beyond the hood and at its inner end having a downturned flange separating said valve from the combustion chamber.

In testimony whereof I affix my signature in presence of two witnesses.

CHARLES R. LAMBERT.
